CLAIM

The ornamental design for a weight scale, as shown and described.

DESCRIPTION

FIG. 1 is a perspective view of a weight scale showing a first embodiment of my new design;

FIG. 2 is another perspective view of the first embodiment;

FIG. 3 is a front view of the first embodiment;

FIG. 4 is a rear view of the first embodiment;

FIG. 5 is a left view of the first embodiment;

FIG. 6 is a right view of the first embodiment;

FIG. 7 is a top view of the first embodiment;

FIG. 8 is a bottom view of the first embodiment;

FIG. 9 is a perspective view of a weight scale showing a second embodiment of my new design;

FIG. 10 is another perspective view of the second embodiment;

FIG. 11 is a front view of the second embodiment;

FIG. 12 is a rear view of the second embodiment;

FIG. 13 is a left view of the second embodiment;

FIG. 14 is a right view of the second embodiment;

FIG. 15 is a top view of the second embodiment; and,

FIG. 16 is a bottom view of the second embodiment.

The broken line portions of the weight scale form no part of the claimed design.
